UNITED STATES PATENT OFFICE.

NICKOLI MILLER, OF NEW YORK, N. Y.

TRAFFIC-DIRECTION SIGNAL.

1,281,192.

Specification of Letters Patent.

Patented Oct. 8, 1918.

Application filed March 30, 1917. Serial No. 158,655.

To all whom it may concern:

Be it known that I, NICKOLI MILLER, a subject of the King of England, residing at 320 East 87th street, New York city, in the county of New York and State of New York, have invented new and useful Improvements in Traffic-Direction Signals, of which the following is a specification.

This invention relates to improvements in traffic direction signals for automobiles.

In carrying out my invention it is my purpose to produce a traffic signal for automobiles or the like which shall be of a simple construction, readily applied to the windshield or front of any ordinary automobile, and having operating mechanism arranged in close proximity to the driver whereby the signal may be operated in an expeditious and convenient manner.

It is a still further object of the invention to produce a traffic direction signal for automobiles or the like including a plurality of fan-like blades arranged upon a suitable axle in a suitable casing, the said blades being either gravity or spring actuated to hold the same in inoperative or non-signaling position, means comprising a flexible element being connected with the shaft and having its end secured to a suitable pivoted member arranged in the body of the machine in a convenient position to be operated by the driver or other occupant of the front seat of the machine which when swung in one direction will draw the flexible element 35 to turn the shaft to bring the signal blades to signaling position, means being further provided whereby the signal may be lighted upon the turning of the blades to such signaling position.

With the above and other objects in view the improvement resides in the construction, combination and arrangement of parts set forth in the following specification and falling within the scope of the appended claim.

In the drawing:

Figure 1 is a front elevation illustrating the application of the improvement.

Fig. 2 is a side elevation, parts being broken away and parts being shown in section.

Fig. 3 is an enlarged sectional view approximately on the line 3--3 of Fig. 2.

Fig. 4 is a sectional view approximately on the line 4--4 of Fig. 2;

Fig. 5 is a perspective view of the operating means;

Fig. 6 is a diagram illustrating the electric circuit for the lamp; and

Fig. 7 is a sectional view approximately on the line 7--7 of Fig. 4.

Referring now to the drawing in detail, the numeral 1 designates the body of an automobile of any desired or preferred construction, the same having arranged thereon the usual windshield 2.

Upon the outer faces of the end members of the frame of the windshield is secured two substantially rectangular members 3 providing the housings for the signals, and the said housings have their outer and if desired their lower faces opened.

Arranged in a suitable casing 4 one upon each of the outer sides of the housing 3 and adjacent to the upper end of the said housing is a drum 5 that is secured to a shaft 6 that passes through bearing openings in the casing whereby one of the ends of the said shaft is received in the housing and the other end projected a suitable distance outward of the casing. The shaft 6 has wound therearound a spring 7 that has one of its ends secured to the casing whereby to revolve the said shaft a predetermined distance in one direction.

To the drum 5 is secured a flexible element 8 that, through the influence of the spring 7, is normally wound around the said drum.

The portion of the shaft 6 extending inwardly of the housing 3 has its end squared, as at 9, the said squared portion 9 being received in the squared opening 10 in a signal blade 11. Other blades 12 and 13 are loosely journaled upon the rounded portion of the shaft, the squared end 9 of the said shaft being secured to the blade 11. The blade 13 is provided with an elongated slot 14, the blade 12 being likewise provided with a similar but shorter slot 15, both of the slots being struck concentric of the pivotal connection of the said blades 11 and 12 to the shaft 6. The blade 10 is provided with a headed member 16, the shank of which passes through the slots 14 and 15 of the blades 12 and 13. By this arrangement it will be noted that when the shaft 6 is turned in a manner which will presently be described, to swing the blade 11, directly connected with the shaft 6, the headed element 16 playing through the slots 14 and 15 will likewise swing the blades 12 and 13 permitting the blade 12 to assume a desired

angle with respect to the blade 11 and likewise the blade 13 to assume an angle with respect to the blades 10 and 11. By this arrangement it will be noted that the signal device comprising the blades will be opened in a fan-shape when the device is in operation and likewise the same will be folded together when moved to within the housing 3 by the spring actuated shaft 6. The outer end of the shaft 6 or the end thereof extending outwardly of the casing 4 is provided with a contact member 17 which is insulated from the shaft proper and which is designed when the signal blades are brought to their outward or signaling position to engage with the electric contact 18. These contacts are in electric circuit with a lamp 20, the said circuit receiving its source of energy from a suitable battery or from the electric energizing device for the spark plugs of the engine of the automobile.

Each of the casings 4 is provided with an opening upon the lower end thereof, the said opening being surrounded by an exteriorly threaded sleeve 21 and upon this sleeve is screwed the outer end of a flexible casing 21. Each of the casings 21 is directed to within the automobile and has its end secured to a slotted lug 22 extending outwardly from a bracket 23, one of the said brackets being connected to the inner face of the dashboard to the opposite sides of the automobile, at any desired location in the said automobile. Upon each of the brackets 23 is pivotally secured, as at 24, an operating lever 25, each of said levers comprising an L or crank shaped element, the shorter angular member of the finger of which, indicated by the numeral 26, being disposed opposite the lug 22 of the bracket 23, while the longer arm 27 of the lever has its outer end formed with an enlargement 28 providing a foot element for the operator. To the finger 26 is secured a flexible element 29 that passes through the flexible casing 21 and through the sleeve 20 of each of the casings 4 there

is secured or may form part of the flexible elements 8 which are wound around the drums 5 in the said casings 4.

The advantage of constructing a signal comprising a blade fixed to a shaft, and a plurality of blades loosely arranged upon the shaft and provided with varying length slots whereby to receive the pin upon the fixed blade and which pin when contacting with the end walls of the slots when the shaft is actuated to turn the same one-quarter of a revolution and to bring the blades to signaling position and when in such signaling position will greatly enlarge or spread the signal, bringing the same to a substantially fan-like shape, will be appreciated as a decided advantage over the ordinary signals which are of a single width either in their operative or inoperative position.

From the above description, taken in connection with the accompanying drawing, the simplicity of the device, as well as the advantages thereof will, it is thought, be perfectly apparent to those skilled in the art to which such invention appertains without further detailed description.

Having thus described the invention, what I claim is:

In a traffic direction signal for automobiles or the like, a housing having an open face, a casing upon one of the sides of the housing, a shaft journaled in the casing and projecting to within the housing, a plurality of blades on the shaft and received in the housing, one of said blades being fixed to the shaft, a pin upon the fixed blade, the remaining blades having different length slots receiving the pin, a flexible element wound around the shaft and extending through the casing, an operating lever for said flexible element, and spring means for turning the shaft to normally retain the signal in the housing.

In testimony whereof I affix my signature.

NICKOLI MILLER.
